UNITED STATES PATENT OFFICE.

FERDINAND POLL MILLER, OF EDDYVILLE, IOWA, ASSIGNOR OF ONE-HALF
TO JAMES B. BICKFORD, OF SAME PLACE.

WASHING-MACHINE.

SPECIFICATION forming part of Letters Patent No. 297,949, dated April 29, 1884.

Application filed September 4, 1883. (No model.)

To all whom it may concern:

Be it known that I, FERDINAND POLL MILLER, a citizen of the United States, and a resident of Eddyville, in the county of Wapello 5 and State of Iowa, have invented certain new and useful Improvements in Washing-Machines; and I do hereby declare that the following is a full, clear, and exact description of the invention, which will enable others skilled in 10 the art to which it appertains to make and use the same, reference being had to the accompanying drawings, which form a part of this specification, and in which—

Figure 1 is a side elevation of my improved 15 washing-machine. Fig. 2 is a plan or top view of the same. Fig. 3 is a vertical sectional view through line *x-x* in Fig. 2, and Fig. 4 is a section on an enlarged scale through line *y-y* in Fig. 1.

20 Similar letters of reference indicate corresponding parts in all the figures.

My invention has relation to certain improvements upon the washing-machine for which Letters Patent of the United States 25 No. 274,140 were issued to me on the 20th day of March, 1883; and the said improvements relate to an improved driving-gear for the machine.

The nature of my said improvements will 30 be fully understood by reference to the drawings hereto attached, in which A represents the tub or suds-box of the machine, B the movable rubber, and C the concave against which the rubber works. The shaft of the 35 rotary reciprocating rubber B has a pinion, D, which meshes with the cogs F of the drive-wheel E, said wheel being provided with another set of cogs, G, which project from the face of the wheel at right angles to the 40 cogs F. H is a short shaft fixed in one side of the machine, upon which the drive-wheel E is journaled; and J is the handle, which is pivoted upon the same shaft between wheel E and the washer I. This handle J has a 45 slot, K, adapted to fit or engage any one of the outwardly-projecting cogs or teeth G, and it is held in engagement with the wheel E by means of the spring L, placed upon the bent end of an arm, M, the inner end of which 50 works upon shaft H between the machine and

the drive-wheel, while its outer bent end is inserted through a slot, K', in the handle or lever J. From this it will be seen that if it is desired to change or shift the position of the handle or lever J in relation to the drive-wheel all that is necessary is to pull the handle outward from the machine, so as to compress the spring L, which releases the slot K in the lever from the tooth or cog G, with which it is engaged, so that the handle may 55 be shifted to any other position upon the drive-wheel, and fixed in place thereon after slot K has been placed opposite to the appropriate tooth by simply letting go of the free end of the handle, when spring L will force it into 60 engagement with the appropriate tooth of the drive-wheel. By this construction and arrangement the handle may be shifted to any desired position for operating the machine, as may be found desirable by the person using 70 it, and this can be done in a moment of time and without in any manner affecting the operation of the machine.

In my Patent No. 274,140 the concave is supported below the rotary reciprocating rubber by rods, the upper ends of which are fastened in springs resting upon the side pieces of the tub; but by my present improvement I support the ends of the concave in curved arms N, which are pivoted at one end upon 80 bolts O, inserted into the suds-box, while the free ends of the arms are connected by coiled springs Q to cleats P, which are fastened on the inside of the suds-box. By this construction the concave is less liable to become displaced than by the construction shown in my patent above referred to, and I also obviate the disadvantages resulting from springs projecting above the suds-box over the arms. 85

Having thus described my invention, I claim 90 and desire to secure by Letters Patent of the United States—

1. The combination of the shaft H, the drive-wheel E, journaled upon said shaft, and having a double set of cogs, F and G, set at right 95 angles to one another, lever or handle J, slotted at K and K', bent arm M, projecting with its free end through slot K', and spring L, constructed and combined substantially as and for the purpose shown and set forth. 100

2. The combination of the suds-box A, rotary reciprocating rubber B, having pinion D, shaft or pintle H, drive-wheel E, having a double set of cogs, F and G, set at right angles to one another, lever-handle J, slotted at K and K', bent arm M, projecting with its free end through slot K', and spring L, all constructed and combined substantially as and for the purpose shown and set forth.

In testimony that I claim the foregoing as my own I have hereunto affixed my signature in presence of two witnesses.

FERDINAND POLLMILLER.
